UNITED STATES PATENT OFFICE.

EMANUEL ESCHELBACHER, OF NEW YORK, N. Y.

CLOTHES-LINE SUPPORT.

1,033,566.

Specification of Letters Patent. Patented July 23, 1912.

Application filed November 2, 1911. Serial No. 658,095.

To all whom it may concern:

Be it known that I, EMANUEL ESCHELBACHER, a citizen of the United States, and a resident of the city of New York, borough of Manhattan, in the county and State of New York, have invented a new and Improved Clothes-Line Support, of which the following is a full, clear, and exact description.

10 Among the principal objects which the present invention has in view are: to provide a support on which laundry may be hung out to dry from the window of an apartment, the parts whereof are manageable from within the room to which the window belongs; to provide a support of the character mentioned with suspension members laterally adjustable to form a passageway through the support; to provide 15 suspension devices for the support operable from within the room from which the window opens to move the laundry to the outer end of the rack; and to provide means for spreading the suspension devices mentioned 20 to form a central passage through the rack.

Two embodiments of the present invention are disclosed in the structures illustrated in the accompanying drawings forming a part of this specification, in which 30 like characters of reference denote corresponding parts in all the views, and in which—

Figure 1 is a perspective view of a support constructed and arranged in accordance with the present invention; Fig. 2 is a plan view of a modified form of the rack shown in operative position; Fig. 3 is a detail view, on enlarged scale and in vertical section, taken on the line 3—3 in Fig. 2; 40 Fig. 4 is a detail view, on an enlarged scale, of the carriers for the hanging lines shown in Fig. 2, the view being shown as a section taken on the line 4—4 in Fig. 2, and Fig. 5 is a detail view showing arrangement of the operating cords for the article supports.

As seen in the accompanying drawings, the rack consists primarily of a metal frame 9. The frame 9 is rectangular in form and 50 provided with three sides, the free ends of the two opposite sides being pivotally mounted upon a cross bar 10. The cross bar 10 is provided in its ends with tapped holes to receive the screw threaded extension 11 of a sliding thimble 12 with which it is integrally formed. The thimbles 12

are each slidably mounted upon guide rods 13, 13. The rods 13, 13 are similar in construction and arrangement to those employed in conjunction with the usual window awnings, it being intended that the bar 10 and frame 9 connected therewith shall be moved up and down on the rods 13 as the rack is adjusted to the requirements or desires of the occupant of the room in front 60 of a window of which the rack is extended.

The connecting side of the frame 9 which is parallel with the bar 10, together with the bar 10, form supports for the sliding rods 14 and tracks for the carriers 15 and 70 clothes lines 16, 16 supported thereon. The rods 14, as shown in Fig. 1 of the drawings, are provided at each end with eyelets 17, 17. The eyelets 17 loosely fit the bar 10 and side of the frame 9 to move lengthwise thereon so that the said rods, if desired, may be clustered or grouped at any point lengthwise of the said bar 10 and opposite side of the frame 9. In the normal operative position of the rods 14 they are 75 disposed as shown in Fig. 1 of the drawings. The clothes are spread on the rods 14, and the same are spaced apart to accommodate the laundry being dried. The operator in moving the rods 14 controls the same from 80 the end adjacent the bar 10.

To raise and lower the frame 9 and rods supported thereby I employ the pull cords 18 which are extended about the pulleys 19, and are permanently anchored at the outer 90 end of the frame 9 and temporarily secured by the cleats 20. To steady the action of the rack I provide a guide rope 21 which is permanently anchored at the head and sill of the window structure, and passes 95 through a guide eyelet 22 formed on the outer side of the frame 9, as seen best in Fig. 2 of the drawings.

In the operation of the invention when embodied in the form shown in Fig. 1 of the drawings, the clothes are spread over the rods 14, the frame 9 being raised or lowered to the horizontal position, as shown. When employing the modified form shown in Fig. 2 of the drawings the clothes are pinned or 100 otherwise secured to one side of the endless lines 16 and are carried out to the proper position on the said lines by operating the other side of the line. For this purpose the carriers 15 consist of strap metal sides having 105 secured at the ends thereof the pulleys 23 and 24. The pulleys 24 are mounted on

the outer end of frame 9 and on cross bar 10, while the pulleys 23 receive the lines 16, as shown best in Fig. 4 of the drawings. It will be understood that in the preferred 5 form a carrier 15 is disposed at the opposite ends of the endless lines 16.

When employing the construction shown in Fig. 2, the outward extension of the frame 9 is practically unlimited. When the length 10 of the side members of the frame and the lines 16 are of such dimension as to prevent the spreading of the carriers 15 at the outer side of the frame, I provide a tackle for spreading and contracting the said lines and 15 the carriers supporting the same at the outer end of the frame 9. This tackle consists primarily of the pull cords 25 and 26. The cords 25 and 26 are each permanently connected to the carriers 15^a and 15^b, respectively, which carriers are disposed adjacent to and at opposite sides of the median line of the frame. The cord 25, which in Fig. 2 of the drawings is carried from the right-hand 20 side of the frame, is there reeved over the guide pulley 27, and is permanently connected with the carrier 15^a at the left of the median line of the frame 9. The cord 26 is reeved over the pulley 28 and permanently connected with the carrier 15^b and at the 25 right of the eyelet 22. In this manner it will be seen that as the cord 25 or 26 is drawn upon, the carriers 15^a and 15^b are respectively moved toward the center of the frame, and to the side thereof. To move the carrier 30 15^b in unison with the carrier 15^a the said carriers are connected by the cord 29. The cord 29 is connected to the carrier 15^a and is carried to the side of the frame and reeved about the pulley 30, and then extended to 35 and connected with the carrier 15^b. By means of this arrangement, it will be seen that when the cord 25 is drawn upon to move the carrier 15^a toward the center of the frame, the cord 29 is drawn upon to move the carrier 15^b toward the center of the 40 frame. To draw on the cord 26 moves the carrier 15^b toward the side of the frame and causes a like movement, but in the opposite direction, of the carrier 15^a. The carriers 45 15, 15 are secured by short loops or other suitable connection with each other and with the master carriers 15^a and 15^b. As the said master carriers are moved away from the

center of the frame 9 to the sides thereof, the carriers 15 are successively impinged 55 upon and moved back by the pressure of the said master carriers to the sides of the frame. When the master carriers are moved toward the center, the carriers 15 are successively drawn upon by the connections between the 60 same until spread in the position shown in Fig. 2 of the drawings. The carriers 15 at the inner side of the frame or mounted upon the bar 10 are adjusted by hand, the bar 10 being convenient for hand adjustment by the 65 operator.

It will be understood that in the inoperative position of the rack, the pull cords 18, 18 are drawn upon, to raise the frame 9 and parts carried thereby to a vertical position 70 and flat against the window frame. In this position it is convenient to dispose the rods 14 and the lines 16 in grouped relation at the extreme sides of the frame 9 to avoid obstructing the window upon which the rack is 75 mounted.

Having thus described my invention, what I claim as new and desire to secure by Letters Patent is:—

1. A clothes line support, having a frame 80 pivotally mounted on the window structure; a set of article supports slidably mounted on each side of the median line of the frame; and means for raising and lowering said frame to free the window opening. 85

2. A clothes line support, having a frame; a set of article supports slidably mounted on each side of the median line of said frame, the members of each set being connected to move together; and means to cause the article supports to simultaneously approach or recede from said median line, said means including a pair of suitably guided actuating cords connected to adjacent members of the sets; a loop cord connecting the adjacent 90 supports of each set, and means for supporting the loop portion of the last-mentioned cord. 95

In testimony whereof I have signed my name to this specification in the presence of 100 two subscribing witnesses.

EMANUEL ESCHELBACHER.
